UNITED STATES PATENT OFFICE

143,402

DESIGN FOR A ROLL ROOFING OR SIMILAR ARTICLE

Abbott Coburn, Chicago, Ill., assignor to Globe Roofing Products Co., Inc., a corporation of Indiana

Application June 23, 1945, Serial No. 120,307

Term of patent 14 years

(CL. D68—1)

To all whom it may concern:

Be it known that I, Abbott Coburn, a citizen of the United States, residing at Chicago, in the county of Cook and State of Illinois, have invented a new, original, and ornamental Design for a Roll Roofing or Similar Article, of which the following is a specification, reference being had to the accompanying drawing forming part thereof,

Figure 1 is a plan view of a portion of a roll roofing embodying the invention; and

Figure 2 is a transverse sectional view along the line 2 of Figure 1.

I claim:

The ornamental design for a roll roofing or similar article, as shown.

ABBOTT COBURN.
